GAS MANTLE HOLDER

Alvin J. McFall, Vista, Calif.

Application March 14, 1955, Serial No. 35,026

Term of patent 7 years

(Cl. D48—10)

Fig. 2.

Fig. 3.

Fig. 1 is a top plan view of a gas mantle holder, showing my new design.

Fig. 2 is a side elevational view thereof, in quarter section.

Fig. 3 is a bottom view.

I claim:

The ornamental design for a gas mantle holder, substantially as shown.
